MASSAGE DEVICE

August F. Luzzi, Wichita Falls, Tex.

Application May 11, 1933, Serial No. 670,578

3 Claims. (Cl. 128—57)

This invention relates to an improved massage device and seeks, among other objects, to provide a device of this character which may be effectively used for massaging the human body.

Another object of the invention is to provide a massage device which is of such construction that rolling, rotary, or oscillating movement upon the surface of the body may be effected.

A further object of the invention is to provide a massage device wherein a plurality of rollers are employed, which rollers are arranged on a number of axes disposed in relatively angular relation.

A still further object of the invention is to provide a device of this character which will be durable, which may be easily applied, and which may be sold at an attractive figure.

And a still further object of the invention is to provide a massage device which will very effectually manipulate the skin tissues so that the obtaining of a complete massage for a given area will be possible.

Other objects of the invention, not specifically mentioned in the foregoing, will be apparent upon reading the following description, taken in conjunction with the appended claims and the drawing.

In the drawing,

Figure 1 is a top plan view of the massage device.

Figure 2 is a fragmentary transverse sectional view taken on the line 2—2 of Figure 1 and looking in the direction indicated by the arrows.

Figure 3 is a longitudinal sectional view taken through a group of the rollers employed.

Figure 4 is an enlarged fragmentary sectional view on the line 4—4 of Figure 2, and

Figure 5 is a fragmentary perspective view showing the construction of the central portion of one of the roller supporting rods employed.

Referring now more particularly to the accompanying drawing wherein like numerals of reference designate like parts throughout the several views, the numeral 1 indicates the body of my improved device. The body is formed from sheet metal and is substantially hemispherical in cross section. The body is relatively wide throughout its central portion and is tapered at its opposite ends. As best seen in Figure 2 of the drawing, the opposite end portions of the body 1 are turned inwardly and upon themselves to define loops 2 and 3. Connecting the lower edges of the loops 2 and 3 is a brace 4 which is substantially U-shaped in vertical section and is provided with upwardly and inwardly disposed end portions 5

and 6. The brace is formed from a strip of heavy metal and will prevent the body from being mutilated, that is to say, the brace retains the body in its hemispherical shape. Extending through the end portions 5 and 6 of the brace 4 are bolts 7 and 8. By referring to Figure 2 of the drawing, it will be seen that the bolts 7 and 8 extend not only through the portions 5 and 6 but also through the wall of the body and through the free end portions of the loops 2 and 3. Said bolts, therefore, serve rigidly to connect the brace with the body and also to connect the free end portions of the loops with the body beneath the brace. It will be seen that the body and brace will be very firmly secured to each other with the consequent result that reinforcement for the entire device will be provided. The brace 4, as will be observed, is of slightly thicker metal than is the body 1, this construction being employed as it is believed that a greater need for strength will be required of the brace, as will be explained hereinafter.

Mounted on the body 1, at its relatively wide central portion and extending at right angles to the length of the body 1 and of the brace 4, is a handle bar 9 and, as best seen in Figure 1 of the drawing, the handle bar is enlarged at both ends to define handles 10 and 11 which are adapted for manual engagement. The bar 9 is formed of wood, or other suitable material, and the handles are of sufficient length to permit ready grasping of the device. Connecting the handle to the body, centrally thereof, is an upwardly extending bolt 12 which is provided with a hexagonal nut 13 at its upper end. Surrounding the central portion of the bar 9 and extending throughout the major portion of the width of the body in overlying relation to said bar is a substantially inverted hemispherical plate 14. The plate 14 is preferably intended for use as a name plate, and suitable indicia may be inscribed thereon. However, the plate 14 may also serve to protect the central portion of the bar 9 and also to cooperate with the nut 13 and bolt 12 for rigidly connecting the bar with the body. Struck up from the body 1, at its enlarged portion and near the edges thereof in lateral alignment with each other and with the bolt 12, are tongues 15 which are adapted to project into the bar 9 and cooperate with the bolt 12 for preventing rotative movement of the bar on the body.

Mounted on the body 1 and extending through the loops 2 and 3 are roller mounting rods which are indicated in general by the numerals 16 and 55

17. Inasmuch as the rods are of substantially identical construction, a description of one will suffice for both. A typical rod consists of a straight medial portion 18 and angularly disposed straight roller-carrying portions 19, which roller-carrying portions are threaded at their outer ends. The rod is bent immediately adjacent the opposite corresponding ends of one of the loops 2 and 3 for disposing the roller-carrying portions so that their axes are in obtuse angular relation to each other and to the body. Formed on the central portion 18 of the rod is a locking lip 20 and, as best seen in Figure 2 of the drawing, the locking lip is adapted to be disposed upwardly within one of the loops 2 and 3 of the body so that axial rotation of the rod within the loop will be prevented. It will, therefore, be seen that the roller-carrying portions will always be presented in the same direction. The rod carried on the opposite end of the body is, as before stated, of identical construction to the above described rod with the exception that the roller-carrying portions are presented in an opposite direction to the roller-carrying portion of the first-mentioned rod. Mounted on each of the roller-carrying portions, at their inner extremities, are stop washers 21.

Rotatably mounted on each of the roller-carrying portions are preferably three spaced rollers 22. The rollers may be formed of wood, or other suitable material, and, as best seen in Figure 3 of the drawing, the outermost roller of each set of rollers is provided with a recess 23. A washer 24 surrounds the outer threaded end portion of the roller-carrying portion 19 and overlying the washer and screwed on said threaded end portion is a cap nut 25. As will be observed, the rollers are slightly spaced apart and are permitted of free rotation on the roller-carrying portions. Carried on each of the rollers is a preferably rubber tire 26 which is circular in cross section and has substantially half its circumference embedded in a hemispherical groove formed on the roller, the tire will thereby be limited from displacement from the roller. By mounting the cap nut 25 within the recess 23 of the outermost roller, the end of the shaft is largely prevented from coming in contact with the bare skin. It is pointed out in this connection that the outermost rollers are mounted at the widest and lowest point possible and their outside surfaces are so arranged that free action of said rollers will be facilitated, this being particularly true when said rollers are embedded into soft skin tissues.

In use, when it is desired to massage a given portion of the body the device is grasped with the hands on the handles 10 and 11. The device is then engaged with the skin and the device may then be rotated on the surface of the skin whereby the skin will be massaged and a very healthy condition created. It is particularly emphasized that, as the sets of rollers are mounted in such a manner, each set is disposed in angular relation to each other set and to the body, the tissues will be massaged in a highly efficient manner in a relatively short time. When the device is rolled over the skin in a direction longitudinally of the body 1, the forward group of rollers will spread the skin tissues from the center of the device and the rear group of rollers will draw the tissues inwardly toward the center of the device. It will, therefore, be seen that the tissues will be kneaded upwardly from the surface of the skin. It will, of course, be understood that when the device is

pulled rearwardly in the opposite direction longitudinally of the body, the operation will be reversed. That is to say, the rear rollers will first spread the tissues and the forward rollers, now at the rear of the device, will draw the tissues inwardly and upwardly for the kneading operation. It is emphasized that irrespective of whether the device is moved longitudinally of the body, or in any other direction, the forward rollers, the planes of which define an obtuse angle, will force the tissues to each side from the center, while the following rollers will force the tissues back again toward the center of the device. A thorough massage will thereby be created. In view of the fact that the rollers are set at opposite angles, the tissues will be manipulated in a criss-cross like manner.

If desired, the device may be used with an oscillatory motion. When the massage is done in this manner, the rollers are first pressed into the tissues of the skin and the handle is turned about the axis of the bolt 12 for a fraction of a rotation and then the turn is reversed. The first fractional turn will vigorously massage the tissues and as the handle is rotated in the opposite direction the tissues will be gently manipulated.

The bar 9 is so mounted on the body 1 that the handles 10 and 11 will be disposed close to the body so that, as the device is being used, danger of tipping the device end-over-end will be prevented. When a completely rotatable massage device is required it is only necessary to remove the handle bar and attach a shaft, or the like, for providing rotatable motion to the device. While I have shown three rollers comprising each set of rollers, it should be understood that any number of rollers desired may be employed.

In view of the fact that the rods are provided at their central portion with the locking lips 20, displacement of the roller-carrying portions and rollers from the desired angular relations will be prevented. The brace 4 will cooperate with the body for preventing spreading of the body and consequent displacement of the rollers.

It is believed that a reading of the foregoing description will render the construction and operation of the device very clear and it is also believed that I have provided a simple and highly efficient massage device which will, if properly handled, very effectually permit an effective massaging operation.

Having thus described my invention, I claim:

1. A massage device including a dome shaped body having loops at opposite portions, a brace extending between the opposed portions of the body and having upwardly extending ears at its ends engaging about said loops and fastened upon the outer face of the body for firmly securing the body and brace to each other and forming a unitary structure, rods extending through said loops and having roller-carrying portions projecting from ends of the loops, rollers carried by said roller carrying portions of said rods, and a handle carried by said body.

2. A massage device including a dome shaped body of sheet metal having tongues at opposite portions bent inwardly and upwardly to form loops, a brace extending between the opposed portions of said body and having ends bent upwardly about the loops and disposed flat against the outer face of the body, removable fasteners passed through the tongues and bent ends of said brace, rods extending through said loops and having end portions extending from ends of the loops and bent to provide roller-carrying portions, and mas-

sage rollers carried by the roller carrying portions of said rods and rotatable thereon.

5. A massage device including a body having bearings extending transversely of the body and having upper portions gradually reduced in diameter, rods having their intermediate portions extending through said bearings and having radially extending lips engaged in the reduced

upper portions of the bearings to prevent turning of the rods in the bearings, said rods having their end portions extending from ends of the bearings and bent to provide diagonally disposed roller-carrying portions, and rollers carried by the extended end portions of said rods.

AUGUST F. LUZZI. [L.S.]
